ERASER HOLDING MECHANISM

Mark E. Savoie, Cleveland, Ohio

Application August 25, 1945, Serial No. 612,589

6 Claims. (Cl. 120—38)

1

My invention relates to new and useful improvements in eraser holding mechanisms and in particular to those mechanisms for propelling or retracting the eraser into the eraser holder.

It is an object of my invention to provide an eraser holding mechanism which includes propel and retract means for the eraser and which may be included as a part of a mechanical pencil.

Another object of my invention is the provision of an improved mounting for the working parts of an eraser propel and retract mechanism which may be used in a mechanical pencil.

Another object of my invention is the provision of an eraser holding mechanism for propelling and retracting an eraser into operative position in which the parts are operatively fastened together and become a part of a mechanical pencil.

A further object of my invention is the provision of an eraser propel and retract mechanism for an elongated eraser which is simple to operate, sturdy in construction, and which may be manufactured at a relatively small cost.

A still further object of my invention is the provision of an eraser holding mechanism which has an elongated screw for propelling or retracting the said eraser.

Still a further object of my invention is the provision of an elongated screw mounted within the barrel of the holding mechanism for engaging the eraser assembly, and means for turning the eraser assembly about this elongated screw, to propel or retract the eraser longitudinally of the screw.

Other objects and a fuller understanding of my invention may be had by referring to the following description and claims, taken in conjunction with the accompanying drawing, in which:

Figure 1 is a perspective view showing one form of my eraser holding mechanism as being a part of a mechanical pencil;

Figure 2 is a partial cross-sectional view of my eraser holding mechanism as used in Figure 1 and illustrating the features of my invention;

Figure 3 is a side view of the eraser retaining cylinder and the inside turning sleeve;

Figure 4 is a side view of the eraser magazine showing the fastening of the eraser support portion to the head portion, which carries the screw;

Figure 5 is a transverse cross-sectional view along the line 5—5 of Figure 3.

My eraser holding mechanism, as illustrated in Figure 1, comprises generally a barrel 10 and an elongated eraser assembly 11 which may be propelled or retracted along an elongated screw 15 supported within the barrel 10. As shown in Fig-

2

ure 1, the barrel 10 may be equivalent to the barrel of the pencil or it may be a barrel constructed for only an eraser holding mechanism. The elongated eraser assembly 11 is carried by an eraser magazine 12 mounted within the barrel. An inner sleeve 13 extending about the eraser magazine 12 and between the eraser magazine and the barrel, and anchored to the barrel 10, is employed to support the eraser magazine within the barrel. A collar 14, frictionally engaging the eraser magazine 12, and abutting the end of the barrel 10 is used to provide a finger-grip surface. To propel or retract the eraser assembly 11 along the screw 15 the operator rotates the barrel 10 with respect to the collar 14, or rotates the collar 14 with respect to the barrel 10.

As shown in Figure 2, the elongated eraser assembly 11 comprises an elongated eraser 19 having an eraser ferrule 20 on one end thereof. The eraser ferrule 20 has a threaded opening 21 for engaging the elongated screw 15. The threaded opening in the ferrule is in alignment with the longitudinal axial opening 22 in the eraser. The cylindrical surface 23 of the eraser frictionally engages the inside surface 24 of the eraser magazine. The eraser magazine 12 includes an eraser support portion 25 and a head portion 26. The elongated screw 15 is non-rotatably fastened in the center of the head portion 26. This screw 15 is mounted in the head portion 26 and extends co-axial of the longitudinal axis of the eraser magazine. An internal circumferential rib 28 on the inside of the support portion 25 and engaging a circumferential groove 27 of the head portion 26 permits revoluble movement of the eraser support portion with respect to the head portion. This rib portion 28 prevents longitudinal movement of the eraser support portion 25 with respect to the head portion 26, and does not allow the eraser to push the eraser magazine 12 out of the barrel 10 of the pencil when the eraser is being ejected. Although I have used the rib portion 28, it is understood that other suitable means may be employed to permit the revoluble movement and at the same time prevent longitudinal movement of the eraser support portion 25 with respect to the head portion 26. The head portion 26 may be non-rotatably fastened with respect to the barrel 10 by a head portion anchor pin 29 extending through the inner sleeve 13, and into the head portion 26. The inner sleeve 13 is anchored to the barrel 10 by an anchor pin 30. Thus it is seen that by turning the support portion 25 of the eraser magazine 12 with respect to the barrel 10 the eraser assembly

is turned about the screw 15 for propelling the same longitudinally along the screw.

The collar 14 has an end portion 35 which extends over the outer end 34 of the inner sleeve 13 and abuts against the end 36 of the barrel. The outer diameter of the collar is substantially equal to the outer diameter of the barrel 10. The inside surface 38 of the collar frictionally engages the outside surface 39 of the eraser magazine and cooperates therewith. An ornamental band 37 may be fastened by suitable means to the collar 14 for extending over the end 35 of the collar and the end 36 of the barrel. This band 37 may be constructed of any suitable material and is employed to make the pencil more attractive to the eye. The collar 14 carries a pocket clip 16 for clipping the pencil in a pocket or for other similar uses. This clip 16 has an extension end 18 which fits in a longitudinal groove 17 on the inside surface of the collar 14. The clip extends outwardly through an opening 31 in the collar at the end of the groove 17. The clip 18 becomes anchored with respect to the collar when the collar is frictionally fitted or slipped over the end of the eraser magazine. The magazine holds the extended portion of the clip within the groove.

In operation, a person using the eraser may rotate the collar in one direction with respect to the barrel, or rotate the barrel with respect to the collar, to propel the eraser outwardly and into operative position. The eraser support portion is prevented from moving longitudinally with the eraser by rotatably fastening it to the head portion. The eraser is rotated with the collar about the screw when the collar is rotated with respect to the barrel. As the eraser turns with respect to the screw it moves longitudinally of the screw. As the eraser moves longitudinally of the screw it is either propelled outwardly or retracted inwardly of the barrel. When the eraser is not in use the operator may retract the eraser inwardly into the eraser holding mechanism by rotating the collar in the opposite direction with respect to the barrel or rotating the barrel in the opposite direction with respect to the collar.

Although I have described my invention with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

This application is a continuation in part of my abandoned application Serial No. 559,037, filed October 17, 1944.

What is claimed is:

1. An eraser holder for an elongated eraser comprising a barrel, an eraser magazine turnably mounted within the said barrel and extending outwardly therefrom for supporting said eraser, an inner sleeve extending about said eraser magazine substantially within the barrel, said inner sleeve being anchored to said barrel for supporting said eraser magazine, said eraser magazine including an eraser support portion and a head portion with the head portion anchored to the said inner sleeve, said eraser support portion rotatably but not longitudinally movable with respect to said head portion, an elongated screw supported by the said head portion and anchored thereto with the elongated screw extending substantially co-axially of the eraser magazine, a collar frictionally fitting about said eraser magazine and

abutting the end of the barrel, said collar and said barrel having substantially equal outside diameters, said eraser and said elongated screw having threadably cooperating means whereby when the collar is rotated with respect to the barrel the eraser is propelled or retracted along the elongated screw.

2. An eraser holder for an elongated eraser comprising, a barrel, an eraser magazine turnably mounted within the said barrel and extending outwardly therefrom for supporting said eraser, an inner sleeve extending about said eraser magazine substantially within the barrel, said inner sleeve anchored to said barrel for supporting said eraser magazine, said eraser magazine including an eraser support portion and a head portion with the head portion anchored to the said inner sleeve, said eraser portion rotatably but not longitudinally movable with respect to said head portion, an elongated screw supported by the said head portion and anchored thereto with the elongated screw extending substantially co-axially of the eraser magazine, a collar frictionally fitting about said eraser magazine and abutting the end of the barrel, said collar and said barrel having substantially equal outside diameters, said eraser having a ferrule on the end thereof and an opening therein, said ferrule having an opening therein and aligned with said opening in the eraser for threadably cooperating with the elongated screw whereby when the collar is rotated with respect to the barrel, the eraser is propelled along the elongated screw.

3. An eraser holder for an elongated eraser having an axially disposed opening, said eraser holder comprising, sleeve means, an eraser magazine turnably mounted within said sleeve means and extending outwardly therefrom for supporting said eraser, said eraser magazine having an eraser support portion and a head portion, said head portion having an annular groove and said support portion having means fitting into said annular groove, whereby the eraser support portion is rotatably but not longitudinally movable with respect to said head portion, an elongated screw non-rotatably supported by said head portion and extending co-axially of the eraser magazine and into the opening of said eraser, said eraser and said screw having cooperating means for propulsion of the said eraser along the said screw by rotation of the said magazine with respect to the said sleeve means.

4. In a mechanical pencil, an elongated feedable and retractible eraser assembly having a threaded opening, a first substantially cylindrical member frictionally engaging and supporting said eraser assembly, a second substantially cylindrical member partially enclosing said first cylindrical member, screw means for engaging the threaded opening of said eraser assembly, support means for supporting and anchoring said screw means to said second cylindrical member, one of said cylindrical members having internal means connected thereto, said internal means having an annular groove, the other of said cylindrical members having radially extending means fitting into said annular groove whereby said first cylindrical member is constrained against axial movement with respect to said second cylindrical member but is turnable therewith for propelling and retracting the eraser assembly along the screw.

5. In an eraser holder for an elongated eraser assembly having a threaded opening, a support member for frictionally engaging and supporting said eraser assembly, sleeve means extending sub-

stantially about said support member, screw means supported within said sleeve means and non-rotatably anchored thereto for threadably engaging the threaded opening of said eraser assembly, said sleeve means having internal means connected thereto, said internal means having an annular groove, said support member having radially extending means fitting into said annular groove whereby said support member is axially constrained but turnable with respect to said sleeve means for moving said eraser assembly axially of the screw means.

6. In an eraser holder for an elongated eraser, a barrel, an eraser holding member carried by said barrel, said barrel having an internal means connected thereto, said internal means having an annular groove, said eraser holder member having

radially extending means fitting into said annular groove whereby said eraser holding member is axially constrained against movement with respect to said barrel, and operative means for moving said eraser axially of said eraser holder.
